HARRY J. WHEELER, OF KANSAS CITY, MISSOURI.

RENEWABLE FUSE PLUG.

Application filed June 14, 1926. Serial No. 115,830.

A further object of the invention is to provide self-cleaning contacts for the terminals and the fuse element.

A further object of the invention is to provide the sockets and plugs with facilities for preventing the metallic spray, incident to the arc formed when the fuse is blown, from forming a short circuit.

A further object of the invention is to provide seats in the plugs to limit the carrying capacity of the same to one fusible element at a time.

I attain these objects and other advantages by means of the device illustrated in the accompanying drawing in which—

Figure 1 is a top plan view of a fuse plug device which embodies my invention, the cap being omitted.

Figure 2 is a longitudinal section of the device through one of the sockets, on the line 2—2 in Figure 1.

Figure 3 is a longitudinal section of the device through the other of the sockets, on the line 3—3 in Figure 1.

Figure 4 is a vertical section through one of the sockets, and showing one of the socket engaging members in operative position therein.

Figure 5 is an elevation of the socket engaging member, and showing the seat for receiving the fuse element, also showing the insulator disk thereon.

Figure 6 is an end elevation of the device.

Figure 7 is a top plan view of the socket engaging member.

Figure 8 is a plan view of the lower end of the socket engaging members, and showing the seats for the fuse elements and the anti-bridging chamber therein and,

Figure 9 is a plan view of one of the fusible elements.

Similar numerals of reference refer to corresponding parts throughout the several views.

Referring to the drawings the numeral 1 designates a block of insulating material, preferably porcelain, having integral therewith twin sockets 2 and 3 and spaced apart transverse ribs 4 and 5. The sockets are formed cylindrical and the upper ends thereof are provided with annular shoulders 6. At diametrically opposite sides of the inner

walls of the sockets are formed guiding slots 7 and 8 and which open in the shoulders 6 and respectively open at their lower ends in 55 the recesses 9, 10, 11 and 12 formed in the lower side of the block 1. Centrally of the sockets and at their lower ends is formed an annular bottom for the sockets and in which are formed transversely extending gaps 13 60 having vertical sides and ends, for a purpose that will be hereinafter explained. A little distance below the shoulders 6 the slots 7 and 8 are formed back to provide a housing for the yielding portions of the terminals 15 65 and 16, as shown at 14 in Figures 2, 3 and 4. The terminals 15 and 16 are made of resilient conducting material, preferably suitable bronze, and are of a suitable length to be formed at right angles to closely fit against the walls of the recesses 9 and 11 and the 70 housings 14 of the sockets. The one end portions of the terminals 15 are connected to binding posts 17 and their free end portions are formed down at an angle to normally extend across the slots 7 to adjacent the upper side of the floor of the sockets, as shown in Figures 2 and 3. The inner end portions of the terminals 16 are formed 75 similar to the form of the terminals 15 and are closely fitted to the walls of the recesses 10 and 12 and the back walls of the housings 14 which communicate therewith and are held to place by screw bolts 18. The bolts 18 holding the terminals 16 associated with 80 the socket 2 are extended upwardly through the body of the block 1 to a pocket 19 and where they are provided with nuts 20. The terminal 16 of the socket 2 is extended upwardly through an opening 21 in the rib 4 and formed to lie upon the body of the block 90 between the ribs 4 and 5. A plate 22 of conducting material is adjustably mounted on the portion of the terminals 16 of the socket 2 by means of a screw 23 which is extended through the plate 22 and then screwed into the terminal to thereby clamp a conductor wire 24 to said terminal. The outer end portions of the terminal 16 associated with the socket 3 is held to place by a screw bolt 100 25 which is extended upwardly through the body of the block 1 and into a metal bar 45 and a conducting plate 26 is adjustably mounted on the upper side of the bar and

impinges on a conductor wire 27. Holes 28 are provided through the block 1 to receive screws to fasten the device to a support.

The twin sockets 2 and 3 are provided with individual socket engaging members 29 which are made of suitable insulator material and comprise cap portions 30 adapted to fit upon the upper ends of the sockets and the annular shoulders 6 at the same time. Centrally of the lower sides of the cap portions are integral cylindrical body portions 31 having diametrically oppositely disposed ribs 32 which are adapted to slidably engage the guiding slots 7 and 8 in the inner walls of the sockets and to engage the yielding portions of the terminals and press the same back into the housings 14. A chamber 33 is formed centrally of the cap portions of the socket engaging members to receive and store therein a supply of fuse elements. A cover 34 is formed to close the chamber 33 and is rotatably mounted on the cap portions. A chamber 35 is formed in the lower ends of the bodies 31 and is provided with vertical sides and ends. Grooved seats 36 are formed in the lower ends of the ribs 32 and communicate with the ends of the chambers 35 and their capacity limited to receive a fusible element 37, one at a time. The fuse element is of a suitable length to project a little distance outwardly of the ribs 32, so that the projecting portions may be folded upward to lie against the outer sides of the ribs 32 to thereby engage the yielding portions of the terminals when the socket engaging member is forced to place in the sockets. A disk 38 of insulator material is mounted on the lower ends of the body portion 31 and is provided centrally with an opening 39 to provide communication between the chamber 35 and chamber 40. A locking device 41 is rotatably mounted between the upper ends of the twin sockets and is adapted to bear down on the shoulders 42 formed in the peripheral edges of the caps and having finger portions 43 adapted to bear upon the upper sides of the caps to hold the socket engaging member closely fitted to the sockets.

To operate the device a fusible element is inserted into the groove 36 of the socket engaging members and the projecting ends thereof folded up against the outer faces of the ribs 32. Then insert the members into the sockets with the ribs 32 entered in the slots 7 and 8 and press the member to place. As the body portion of the members goes down the folded end portions of the fusible elements engage the yielding portions of the terminals and closes the circuit and, thereafter, forcing the yielding portions of the terminals back into the housings 14. The reaction of the yielding portions of the terminals effects a positive contact of the fuse element with the terminals. The sliding

contacts of the fuse elements with the terminals makes the contact surfaces self-cleaning. The capacity of the grooves 36 being absolutely limited to hold a single fusible element eliminates all danger of inadvertently making a short circuit by installing more than one fuse element at one time. The gaps 13 extending at right angles to the fuse element and having vertical faces prevent the spraying of particles of the fuse element when blown to bridge the sockets, thereby preventing a short circuit by the arc incident to a blown fuse. Likewise the vertical faces of the chambers 35 are kept free from metallic particles from a blown fuse. The fire flashes incident to the arc of the blown fuse are confined to the interior of the sockets by the precision of the adjustment of the cap portions of the socket engaging members to the sockets and the locking of the same to place by means of the locking device 41 to which power is applied by the pressure of the screw 44. When a fuse is blown the socket engaging member is pulled from the socket and the fragment portions of the fuse may be readily shaken from their seats and a new fuse placed as hereinabove described. When the socket engaging member is pulled from its socket the yielding portions of the terminals involved spring back to their normal positions.

The electric circuit is from line wire 24 to terminal 16 associated with socket 2, fuse element 37, terminal 15 to binding post 17 and over a circuit having resistance, not shown, to binding post 17 associated with the socket 3, terminal 15, fuse element 37, terminal 16, bolt 25, bar 45, plate 26 to line wire 27.

Having described my invention what I claim is—

A renewable fuse plug, consisting of an insulator body having twin non-metallic sockets provided with inner annular shoulders and with diametrically opposite guiding slots opening at their upper ends in the shoulders and having portions of the slots cut back to form housings, the floors of said sockets having recessed gaps therein provided with vertical faces, terminals extending into the housings in said sockets and having angularly disposed yielding portions normally extending inwardly of the sockets, non-metallic individual socket engaging members having diametrically opposite ribs on their sides adapted to slidably engage the guiding slots in said sockets and slidably press back the yielding portions of said terminals into the housings in the sockets and cap portions adapted to close the upper ends of the sockets and the guiding slots therein, the lower ends of said socket engaging members having recessed gaps therein provided with vertical walls and located between the ribs thereon and fuse engaging grooves in

the ends of the ribs communicating with said gaps in the members, said grooves being limited to receive single fuse elements and non-metallic washers mounted on said members to hold the fuse elements in place, and fusible elements loosely carried by said socket engaging members and having their end portions formed up on the outer sides of

the ribs thereon and adapted to slidably contact the yielding portions of said terminals when the socket engaging members are pushed to place in the sockets. 10

Dated Kansas City, Missouri, June 10, 1926.

HARRY J. WHEELER.
